ELECTRICAL REGISTERING SYSTEM.

1,250,854.

Specification of Letters Patent.

Patented Dec. 18, 1917.

Application filed June 29, 1916. Serial No. 106,603.

To all whom it may concern:

Be it known that I, CHARLES L. GOODRUM, a citizen of the United States, residing at New York, in the county of New York and 5 State of New York, have invented certain new and useful Improvements in Electrical Registering Systems, of which the following is a full, clear, concise, and exact description.

10 The present invention relates to electrical registering systems where it is desired to register the number of successful connections made, and particularly to a party line telephone registering system. In a party line system, it is especially desirable to indicate the number of successful calls made by the individual parties on the same party line.

An object of the invention is to effect individual metering of connections made by 20 individual branches of the same line. Another object is to effect the association of the registering circuit with the metering device individual to the branch of the line 25 making the connection. A further object is to effect this association through means which are necessarily actuated in obtaining a connection, and which, when actuated, automatically produce a series of impulses 30 peculiar to the individual branch of the common line, to effect association of the meter circuit with the proper party meter. Still another object is to insure that a successful connection has been made before the 35 meter is operated.

The invention is shown as applied to both manual and full automatic telephone systems, but is obviously applicable to semi-automatic telephone systems and to other 40 uses.

In the drawings, Figure 1 represents diagrammatically an application of this invention to a manual telephone system; while Fig. 2 shows an application thereof to a full 45 automatic telephone system, the usual apparatus individual to a party line being shown above and to the left of the dotted lines, the registering apparatus associated with said line being shown below and to the 50 left of said dotted lines, while a trunk selector and called station are shown to the right of the vertical dotted line.

Referring first to the manual system, which can be best understood from a description of its operation, a^1 , a^2 , a^3 , and a^4

represent subscribers' sets on the same party line, the subscriber's circuit being shown for a^1 , which will be assumed to be party IV. Associated with each set is an impulse mechanism 1, which, on actuation, automatically sends a series of impulses differing in character for each of the individual stations on the party line. The sender 1, as shown, is arranged so that on each operation it will move its impulse wheel one complete 60 revolution, and stop in the position shown. The wheel shown represents party IV, whereas wheels differing only in the number of teeth would be used for the other stations on the line. For example, party I 65 would have three less teeth, party II, two less, and party III, one less tooth on the wheel than party IV.

In operation, the called party pulls down his sender, which, in the case of party IV, 70 results in controlling a circuit which is closed for four short intervals, and then completed for a long interval, and again opened with the sender in normal position. On the first completion of this circuit, a 75 high resistance relay 2 is energized through a circuit leading from ground, the contact spring of sender 1, conductors 3, 4, 5, relay 2, conductor 6, back contact and left-hand armature of cut-off relay 7, conductor 8, 80 line signal 9, to grounded battery. Battery is also provided through a line relay 10 and conductor 11, joining the circuit previously traced at the left-hand armature of the relay 7. Due to the high resistance 85 of relay 2, the line signal 9 will not light, and the relay 10 will not pull up. Upon the energization of the relay 2, a circuit is completed for a slow release relay 12 over a 90 circuit extending from ground, right-hand armature and back contact of relay 7, conductor 13, armature and front contact of relay 2, conductors 14 and 15, relay 12, to grounded battery. Relay 12, on energization prepares a circuit for a slow release relay 16 and a stepping magnet 17 of 95 the metering mechanism. The first momentary breaking of the circuit by the impulse wheel of the sender 1 allows the armature of the relay 2 to fall back, momentarily 100 completing a circuit to the stepping magnet 17. This circuit extends from ground, right-hand armature and back contact of relay 7, conductor 13, armature and back contact of relay 2, conductor 18, left-hand armature 105 of relay 16, and the coil of the stepping magnet 17. This circuit extends from ground, right-hand armature and back contact of relay 7, conductor 13, armature and back contact of relay 2, conductor 18, left-hand armature 110 of relay 16, and the coil of the stepping magnet 17.

and front contact of relay 12, conductors 19 and 20, stepping magnet 17, to grounded battery. Magnet 17, on energization, attracts armature 21, moving a stepping pawl 22. The pawl 22 moves a ratchet wheel 23 one step, carrying an arm 24 one step, bringing said arm to rest on a contact 25 leading to operating magnet I, controlling a counter 26 individual to party I of the calling line. 5 The arm 24 is held in this position by a locking pawl 27 which was placed in locking position on energization of the relay 12. The relay 16 was energized at the same time as magnet 17 over a circuit common with 10 that of said magnet, through the conductor 19, from whence a conductor 28 extends the circuit to relay 16 and grounded battery. On the first movement of the arm 24, off-normal contacts 192 and 193 were closed but 15 the energization of relay 16 prevented shunting of the relay 2 by opening the line between its armature and back contact. On the circuit originated by the sender 1 being momentarily made and momentarily 20 broken, stepping magnet 17 is again actuated to move its arm to contact 29 and the next energization of the relay 2 with the subsequent momentary deenergization will move arm 24 to contact 30, while still another will move it to contact 31 extending 25 to the operating magnet IV of the counter individual to party IV. The circuit through the magnet 2 is then completed for a longer interval and its armature held up sufficiently long for the relay 16 to be deenergized, whereupon its armature will close a 30 circuit shunting out the relay 2 over the following circuit: ground, contact spring of sender 1, conductors 3, 4 and 5, 32, armature and back contact of relay 16, conductor 33, 35 contact 192, conductors 34, 6, back contact and left-hand armature of relay 7, conductor 11 and line relay 10 to grounded battery. Line relay 10 pulls up, completing a locking circuit for itself from ground, conductor 35, through its left-hand armature and front contact, conductors 36, 6, back contact and left-hand armature of relay 7, conductor 11, relay 10, to grounded battery. 40 The line signal is now illuminated at full brilliancy, the high resistance relay 2 having been shunted from its circuit. The relay 10 also maintains a circuit for the energization of the release relay 12 over a circuit from ground, right-hand armature and front contact of relay 10, conductor 37, contact 193, conductor 15, relay 12, to grounded battery. The sender will have reached its 45 normal position by this time, removing any possibility of further ground therefrom.

The subscriber will have removed his receiver prior to this time, and the line signal 9, being now fully illuminated, will attract the attention of the operator, who will take 50 the answering end of an idle cord and insert

the plug 38 thereof into the jack 39 to which the conductors of the calling line are secured. The cut-off relay 7 is actuated over a circuit from grounded battery, relay 7, conductor 40, sleeve contact of jack 39, sleeve of the plug 38, resistance 44, conductor 41, registering key 42, in its normal position, to ground. Immediately upon pulling up, the relay 7 completes a maintaining circuit for the release relay 12 over a circuit extending from ground, right-hand armature and front contact of relay 7, conductor 37, contact 193, conductor 15, relay 12, to grounded battery. Relay 7, on pulling up, also opens the circuit of the line signal 9 and also the circuit of the line relay 10 which thereupon falls back. A circuit is also completed for the operating magnet IV from grounded battery, operating magnet IV, contact 31, arm 24, conductors 43 and 40, test contact of jack 39, sleeve of plug 38, and through resistance 44 of conductor 41, and registering key 42, in its normal position, to ground. The magnet, however, will not pull up at this time as it is so made that it will not operate through the battery normally associated therewith, but requires a stronger battery for operating.

On the operator's pressing the listening key 45, she connects in an operator's set 46, and the talking circuit of the subscriber is now extended over the conductors 4 and 47 through jack 39 and plug 38, and conductors 48 and 49 of the answering part of the cord and a repeating coil to the conductors 51 and 52 of the calling end of the cord and through listening key 45 to the operator's set. The operator can now converse with the calling party. The operator would then use the calling end of her cord to extend the calling line to the line called in the usual manner. Magnets 53 and 54 in the conductors 48 and 51 would control the supervisory signals of the calling and called parties, respectively, and on the operator's learning that the called party has responded, the registering key 42 would be depressed and furnish added battery 50, which, acting in series with the battery of the operating magnet IV, would cause it to pull up its armature and step the counter associated therewith one step, thus registering a successful call. The particular cord circuit used forms no part of the present invention, as any cord circuit could be used which has a sleeve with a registering key normally grounded, and which, when operated, would connect a battery in series with the battery of the operating magnets.

On either party's hanging up, this fact would be indicated to the operator by one of the supervisory signals 53, 54, whereupon the operator would pull down the cord. Relay 7 would then be deenergized, opening the circuit to the release magnet 12. Release

magnet, on being deenergized, allows the holding pawl 27 to be withdrawn from engagement with the wheel 23, whereupon the arm 24 will be returned to normal by a 5 spring attached thereto. The off-normal contacts would now be open and the device ready for subsequent use.

Referring now to the application of this invention to a full automatic telephone system as shown in Fig. 2 of the drawings, A¹, A², A³ and A⁴ represent subscribers' sets on the same party line, the substation circuit being shown for A⁴, which will be assumed to be party IV. Associated with each set 10 is a sender mechanism 101 arranged to send a preliminary series of impulses on removal of the receiver and actuation of a preliminary sender. The number of impulses sent differs according to the station of the party 15 line and acts to connect the proper counter with the calling line. Two sets of contacts are shown in the sender, one being under the control of a preliminary sender, and the other set being under the control of the subscriber in setting up the call. A type of 20 sender which could be used for this purpose is more fully described in application of C. L. Goodrum and L. Von Nagy, Serial No. 94,846, filed May 1, 1916, and reference is 25 made thereto for more detailed description. The invention is not limited to use with this type of sender, however, as any sender which will send impulses differing for the station of the party line at which it is used, may be 30 utilized. The different subscribers in the same party line come into an exchange over common line conductors, as 103 and 104, extending respectively through the inner left-hand armature and back contact, and the 35 right-hand armature and back contact of a cut-off relay 107. A conductor 106 extends from the back contact of the inner left-hand armature of relay 107 through line relay 105 to ground. Removal of the calling subscriber's receiver completes a circuit from 40 ground, left-hand winding of relay 105, conductor 106 back contact and inner left-hand armature of relay 107, conductor 103, sender 101, and subscriber's set A⁴, conductor 104, 45 right-hand armature and back contact of relay 107, conductor 128, high resistance relay 109, conductors 110 and 111, and right-hand winding of relay 105, to grounded battery. The resistance of relay 109 is so high that 50 the relay 105 does not pull up. The relay 109 pulls up, however, and completes a circuit for a slow release relay 112, over a circuit from ground, armature and front contact of relay 109, conductor 113, relay 112, 55 to grounded battery. Relay 112 pulls up, preparing a circuit for a slow release relay 108, and a stepping magnet 115 of the registering mechanism. Preliminary impulses are now sent and, on the first break, relay 60 65 109 is deenergized and its armature falls

back, completing a circuit for the relay 108, extending from ground, armature and back contact of relay 109, armature and front contact of relay 112, (slow to release), conductor 114, relay 108 to grounded battery. Relay 108 pulls up opening a part of shunt circuit about the relay 109. A circuit was also produced for the stepping magnet 115, extending from conductor 114 of the circuit previously traced, conductor 116, stepping magnet 115, to grounded battery. Magnet 115 being energized attracts its armature 117, carrying a pawl 118 engaging a ratchet wheel 119 to move the same one step. The ratchet wheel 119 carries an arm 120, which has thus been moved to engage contact 121 associated with the operating magnet I of the counter individual to party I. On movement of arm 120, off-normal contacts 192 and 193 controlled thereby are closed. Contacts 122, 123 and 124 are contacts associated respectively with the operating magnets II, III, and IV of the counters individual to party lines II, III, and IV. The arm 120 is held in the position to which it is moved 90 by a holding pawl 125. The operating magnets control the counters by attracting an armature 126 carrying a pawl which steps counter wheel 127 one step on each operation. 95

Three other momentary interruptions of the circuit are produced by the sender 101 and step the arm 120 to position the same on the contact 124. The relay 109 pulls up for a longer time, whereupon the relay 108 100 is deenergized and its armature falls back, completing a shunt circuit around the high resistance relay 109. This circuit extends from ground, left-hand winding of line relay 105, conductor 106, inner left-hand armature and back contact of relay 107, conductor 103, subscriber's set, conductor 104, right-hand armature and back contact of relay 107, conductors 128, 130, contact 192, conductor 131, back contact and armature 105 of relay 108, conductor 129, 111 and right-hand winding of relay 105 to grounded battery. Relay 105 now pulls up, completing a circuit from ground, right-hand armature and front contact of relay 105, conductor 132, left-hand winding of line switch magnet 133, to grounded battery. Line switch magnet 133 pulls up its armature 134, forcing the plunger 135 into the contact springs of a preselected trunk. This plunger forces 110 the contact springs 136, 137 outwardly and closes a circuit extending from grounded battery of the operating magnet IV, contact 124, arm 120, conductor 138, right-hand windings of line switch magnet 133, conductor 139, cut-off relay 107, conductor 140, contact spring 137, conductors 141, 142, relay 143, conductor 144, and back contact and armature of relay 145 to ground. Operating magnet IV will not pull up at this 115 120 125 130

time, due to the combined resistance of line switch magnet 133, cut-off relay 107 and relay 143 in series therewith. Relay 143, on energization, completes a circuit from 5 ground, front contact and armature of relay 143, conductor 179 to switch 146, which controls a circuit for moving the master switch with other idle plungers to a position ready for association with the next idle 10 trunk. Cut-off relay 107 is energized and pulls up, extending the calling line to a trunk selector by a circuit extending from ground, armature and back contact of relay 145, conductor 144, relay 143, conductors 142, 15 141, contact spring 137, conductor 140, front contact and right-hand armature of relay 107, conductor 104, subscriber's set, conductor 103, inner left-hand armature and front contact of relay 107, conductor 147, 20 contact spring 136, conductor 148, and an arm 149 of the selector side switch in its first position, conductor 150, and relay 151, to grounded battery. Relay 151 then pulls up, completing a circuit for a slow release 25 relay 152 extending from ground, armature and back contact of test relay 153, armature and front contact of relay 151, conductors 154 and 155, and relay 152 to grounded battery. Relay 152 on energization prepares 30 a circuit for the rotary or primary stepping magnet 156 and also for a slow release relay 157.

The calling subscriber then operates his 35 sender to set up a call and on each interruption the armature of relay 151 falls back, completing a circuit from ground, armature and back contact of relay 153, conductor 158, left-hand armature and front contact of relay 152, conductors 159 and 160 to the rotary 40 magnet 156, which rotates the finder brush the number of steps corresponding to impulses set up by the subscriber. The relay 157 is energized over a branch circuit extending from conductor 159 of the circuit 45 previously traced, conductor 161, and relay 157 to grounded battery. Relay 157 pulls up, completing a circuit from ground and its armature and front contact, conductor 162, through side switch escapement magnet 50 163. This magnet 163 remains energized until the rotary impulses have been sent, whereupon relay 151 is energized sufficiently long to let the slow release relay 157 drop back, de-energizing relay 163. On this de- 55 energization the circuit control switch arms are moved to second position.

Immediately upon going to second position, a circuit is completed from ground, armature and back contact of relay 153, 60 armature and front contact of relay 151, conductors 154, and 164, side-switch arm 165, at second position, conductor 166, rear contact and armature of the vertical magnet 167, to grounded battery. The magnet 167 65 interrupts its own circuit and steps the

brushes of the trunk selector upwardly until the brushes of the switch associated with the conductors 168 and 169, encounter an idle trunk which is represented by the presence of test ground upon its contact 170. 70 As soon as an idle trunk is reached, a circuit is completed, energizing the test relay 153 by a circuit extending from test ground contact 170, brush conductor 169, conductor 171, relay 153, to grounded battery. Relay 75 153 pulling up completes a circuit for the escapement magnet 163, extending from ground, armature and front contact of relay 153, conductor 172, right-hand armature and front contact of relay 152, which is 80 slow to release, conductors 173 and 174, and escapement magnet 163 to grounded battery. On this energization, the escapement magnet moves the side-switch arms to third position.

In the third position, the test ground is 85 removed and relay 153 de-energized by the operation of the next switch (not shown) in the well-known manner. The call would now be put through selectors and connectors until the called party 180 was reached and 90 would be rung in any desired manner, such means not being considered any part of this invention. In this position, a polarized relay 175 has been placed in a circuit, so that on the called party's removing his receiver, 95 a circuit having a polarity such as to operate the polarized relay 175 would be completed from grounded battery, relay 153, conductors 171, 169, called subscriber's set 180, conductor 168, polarized relay 175, conductor 100 176, circuit control switch arm 149, conductor 148, spring contact 136, conductor 147, front contact and inner left-hand armature of relay 107, conductor 103, subscriber's set A⁴, conductor 104, right-hand armature and 105 front contact of relay 107, conductor 140, spring contact 137, conductors 141 and 142, relay 143, conductor 144, back contact and armature of relay 145 to ground. Polarized relay 175 pulling up would shunt out the 110 relay 143 from the circuit previously traced to the operating magnet IV, thus reducing the resistance to such an extent that the operating magnet IV would pull up, actuating its counter 127. This circuit extends from 115 ground, inner armature of polarized relay 175, conductors 177, 141, contact spring 137, conductor 140, relay 107, conductor 139, right-hand winding of magnet 133, conductor 138, arm 120, contact 124, and operating 120 magnet IV to grounded battery. A circuit is also completed for the escapement magnet 163, extending from ground, front contact and outer armature of polarized relay 175, conductor 178, front contact and armature 125 of escapement magnet 163, conductor 174, and escapement magnet 163, to grounded battery. The escapement magnet pulls up, interrupting its own circuit, and steps the circuit control switch arms to the fourth 130

position. In this position the talking circuit is completed between the calling party and the one called, the fluctuating voice current being free to pass a condenser 181 inserted 5 in the circuit to prevent the passage of direct current.

When the called party hangs up, ground is put on test terminal 170, completing a circuit for the test magnet 153. This circuit 10 extends from ground, 170, over conductors 169, 171, through relay 153, to grounded battery. Relay 153, on energization, completes a circuit for the release magnet 145, which operates to restore the trunk selector 15 with its circuit control switch to normal position. This circuit extends from ground, armature and front contact of relay 153, conductor 172, right-hand armature and back contact of relay 152, conductor 186, side- 20 switch arm 187, in its fourth position, off-normal contact 188, conductor 189, through release relay 145 to grounded battery. Relay 145 pulling up completes a locking circuit for itself, extending from ground 25 through its armature and front contact, conductor 191, off-normal contact 188, conductor 189, through itself to grounded battery. This operates until the parts are restored to normal, in which position the off-normal 30 contact 188 is opened and relay 145 deenergized.

Should the calling subscriber hang up before connection has been made through the trunk selector, restoration to normal is accomplished 35 over a circuit for the release magnet 145, extending from ground, armature and back contact of test relay 153, armature and back contact of relay 151, conductor 158, left armature and back contact of 40 relay 152, conductor 190, side-switch arm 187, in first or second position, off-normal contact 188, conductor 189, and relay 145 to grounded battery. Relay 145 would complete a locking circuit to operate the same 45 until the switch was restored to normal position as previously described. Should the calling party hang up when the circuit control switch arms were in the third position, release of the selector shown would be under 50 the control of the next switch, which would be released in the well-known manner, and supply ground to contact 170, from which point the release is as previously described. On the release of the selector, the cut-off 55 relay 107 is deenergized, whereupon the release magnet 182, controlling the release of the arm 120, is energized. Its circuit extends from ground, armature and back contact of relay 109, armature and back contact of relay 112, conductor 184, back contact and outer left-hand armature of relay 107, conductor 185 and contact and left-hand armature of relay 105, conductor 183, release magnet 182, off-normal contact 193 to grounded 60 battery. Magnet 182 pulling up withdraws 65

the holding pawl 125 from the ratchet wheel 119, whereupon the arm 120 returns to normal.

In the normal position of arm 120, it is associated with grounded battery so as to 70 complete a circuit to operate the cut-off relay 107 when the connection is made to the contacts 193, 194 used when the party line is the called line.

If desired, the arm 24 of the manual system or the arm 120 in the full automatic system, might be made to normally rest on the contact connected to the operating magnet 1 individual to party I in both systems. In this case, the impulse sender could be omitted for party I in both systems and parties II, III and IV step the arm one, two and three steps, respectively, to associate the same with their respective operating magnets. 75 80 85

What is claimed is:

1. In a metering system, a line having a plurality of branches, metering means individual to each of said branches to keep an individual meter record thereof, means individual to each branch for transmitting a series of impulses over said line, means actuated in response to the series of impulses transmitted from each branch to associate with said line the metering means individual to the branch desiring the connection, and means beyond the control of the branch to effect actuation of the individual metering means thus associated with said line. 90 95

2. In a metering system, a line having a plurality of branches, a metering means individual to each of said branches to keep an individual meter record thereof, means individual to each branch for transmitting a different series of impulses to associate the proper metering means with said line, and means to operate the metering means so associated. 100 105

3. In a metering system, a line having a plurality of branches, an impulse means individual to each of said branches for transmitting series of impulses over said line, a metering means individual to each of said branches to keep an individual meter record thereof, means controlled by the series of 110 impulses initially transmitted by the impulse means of the branch desiring a connection to associate the metering means individual to that branch with said line, and means to actuate the metering means so associated. 115

4. In a metering system, a line having a plurality of branches, metering means individual to each of said branches to keep an individual meter record thereof, means common to all the branches of said line to associate the metering means with said line, individual means associated with said branches to transmit different series of impulses to said common means to actuate said common means to cause the same to associate with 120 125 130

- 6 said line the metering means individual to the branch whose actuating means is operated, and means to operate the metering means so associated.
- 5 5. In a metering system, a line having a plurality of branches, metering means individual to each of said branches to keep an individual meter record thereof, an impulse means associated with each branch to produce identifying series of impulses individual to said branch, means actuated by said identifying series of impulses to associate with said line the metering means corresponding to the branch in which the 10 identifying series of impulses are produced, and means to actuate the metering means so associated.
- 10 6. In a metering system, a line having a plurality of branches, metering means individual to said branches to keep an individual meter record thereof, another line to which connection is desired, means for establishing such connection, impulse transmitting means individual to each branch 15 for transmitting a series of impulses to control said connections, means controlled by the initial series of impulses transmitted by said transmitting impulse means for associating with said line the metering means 20 individual to the branch desiring such connection, and means for operating the metering means individual to such branch on obtaining such connection.
- 20 7. In a metering system, a line having a plurality of branches to keep an individual meter record thereof, metering means individual to said branches, means to send special series of impulses differing for the different branches of said line, means actuated 25 by said series of impulses to associate with said line the metering means individual to the branch represented by the series of impulse transmitted, and means to operate the metering means so associated.
- 25 8. In a metering system, a line having a plurality of branches, another line to which connection is desired, metering means individual to said branches, means to control the production of identifying series of impulses differing for the different branches, means actuated by said series of impulses to associate with said first line the metering means individual to the branch represented by the series of impulses produced, means 30 to establish connection between said lines, and means to insure the association of said metering means with said first line before connection between said lines can be completed.
- 30 9. In a metering system, a line having a plurality of branches, another line to which connection is desired, metering means individual to said branches, means to control the production of identifying series of impulses differing for the different branches, 35 means actuated by said series of impulses to associate with said first line the metering means individual to the branch represented by the series of impulses produced, means to establish connection between said lines, and means to insure actuation of said control means before connection between said lines can be effected.
- 35 10. In a metering system, a line, impulse controlling means therefor, metering means for association with said line, means controlled by said impulse means to associate said metering means with said line, a line relay, a second relay, a circuit normally including said relays in series, said second relay normally preventing said line relay from operating, and means for removing the second relay from the circuit of the line relay to actuate said line relay after the impulses to associate said metering means with said line have been sent.
- 40 11. In a metering system, a line, a line switch therefor, a second line, means to extend said line from said line switch to said second line, a metering means for said first line, means to associate said metering means with said first line, means to operate said line switch after association of said metering means with said first line, and means to operate said metering means.
- 45 12. In a metering system, a line, a line switch therefor, a second line, means to extend said line from said line switch to said second line, a metering means for said first line, means to associate said metering means with said first line, means to prevent operation of said line switch until after said metering means has been associated with said first line, and means to operate said metering means after connection of said lines.
- 50 13. In a metering system, a calling party line having a plurality of branches, a called line, means to interconnect said lines, metering means individual to said branches of the calling line to keep an individual meter record thereof, impulse transmitting means individual to each branch of the calling line for transmitting series of impulses to control the interconnection of said lines, means controlled by the initial series of impulses transmitted by said impulse transmitting means for associating with said calling line the metering means individual to the branch desiring such connection, and means automatically actuated on response of the called line to operate said associated metering means.
- 55 14. In a telephone system, a line having a plurality of stations, impulse controlling means providing upon this initial operation different series of impulses for each of said stations, metering means individual to each of said stations to keep an individual meter record thereof, and means controlled by the initial operation of the impulse means of a
- 70 75 80 85 90 95 100 105 110 115 120 125 130

station to associate the metering means individual to said station with said line, and means to actuate the metering means so associated.

- 5 15. In a telephone system, a party line having a plurality of stations thereon, metering means individual to each of said stations to keep an individual meter record thereof, another line to which connection is 10 desired, means to establish connection between said lines, means individual to each station for transmitting a series of impulses over said line, means actuated in response to the series of impulses transmitted from each 15 station to associate with said line the metering means individual to the station desiring connection, and means operated on obtaining connection with the line to which connection is desired to actuate the metering 20 means so associated.

16. In a telephone system, a party line

having a plurality of stations, metering means individual to each station to keep an individual meter record thereof, other lines to which connection may be made, means to 25 establish connection between said party line and any desired one of said other lines, means individual to each station for transmitting a series of impulses over said line, means actuated in response to the series of 30 impulses transmitted from each station to associate with said line the metering means individual to the station desiring connection, means operated on obtaining connection with the line to which connection is desired to actuate the metering means so associated, and means to restore said system 35 to normal when connection is no longer desired.

In witness whereof, I hereunto subscribe 40
my name this 28th day of June A. D. 1916.

CHARLES L. GOODRUM.
